WHEELED TOY

Ernest L. Thornell, East Aurora, N.Y., assignor to Fisher-
Price Toys, Inc., East Aurora, N.Y., a corporation of
New York

Filed Mar. 1, 1965, Ser. No. 84,005

Term of patent 14 years

(Cl. D34—15)

FIG. 1

FIG. 2

FIG. 3

FIG. 4

FIG. 5

FIG. 6

FIG. 1 is a perspective view of a wheeled toy showing my new design;

FIG. 2 is a perspective view on a slightly smaller scale as viewed from the other side thereof and showing the handle in forward position;

FIG. 3 is a side elevation thereof in a larger scale;

FIG. 4 is a top plan view thereof;

FIG. 5 is a front elevation thereof, and

FIG. 6 is a rear elevation.

The broken lines indicating building blocks in FIG. 4 are for purposes of illustration only.

I claim:

The ornamental design for a wheeled toy, substantially as shown and described.
